UNITED STATES PATENT OFFICE.

CLARENCE SCHERER, OF CENTER, NORTH DAKOTA.

LAPPING-TOOL.

1,382,552.

Specification of Letters Patent. Patented June 21, 1921.

Application filed June 29, 1920. Serial No. 392,630.

To all whom it may concern:

Be it known that I, CLARENCE SCHERER, a citizen of the United States, residing at Center, in the county of Oliver and State 5 of North Dakota, have invented new and useful Improvements in Lapping-Tools, of which the following is a specification.

The present invention has reference to a lapping tool especially desirable for tapping bushings of automobiles, and, of course, 10 adaptable for tapping the openings in other articles.

The primary object is the production of a lapping tool in which the tapping elements 15 are brought against their work by centrifugal force.

A further object is to produce a lapping tool in which a plurality of loosely connected abrasive members are arranged upon a 20 shank and which are spring influenced so as to arrange the same normally against the shank, so that the tool may be readily positioned in the opening whose wall it is to lap, the shank being attached to a drill or 25 similar implement whereby a rapid rotary motion is imparted thereto, and such centrifugal motion causing the abrasive members to be moved automatically away from the shank against the spring influenced means 30 to engaging position with the wall of the opening to be lapped.

A further object is the production of a lapping tool in which the abrasive members are influenced by a centrifugal force imparted to the member carrying the same, so that 35 the said members will move away from the member to engage with the wall of the opening to be lapped, and also whereby walls of openings of various sizes may be properly 40 lapped by the same instrument.

A further object is the production of a centrifugally influenced lapping tool in which the reaming or cutting elements are in the nature of abrasive fabrics and in 45 which the jaw members on which the said fabrics are arranged have simple means for retaining the same thereon, whereby such fabrics may be readily attached, and readily removed when worn.

The foregoing objects, and others which 50 will appear as the nature of the invention is better understood, may be accomplished by a construction, combination and operative arrangement of parts, such as is illustrated 55 by the drawings.

In the drawings:

Figure 1 is a side elevation of the improvement.

Fig. 2 is a similar view but showing the jaws spread as when the same are being resolved.

Fig. 3 is a sectional view approximately on the line 3-3 of Fig. 1.

Fig. 4 is a detail view of one of the jaws, illustrating the manner in which the abrasive cloth is clamped thereon.

My improvement is designed to have its shank received in the chuck of a drill so that a rapid rotary movement is imparted thereto.

The improvement includes a shank 1 that 70 has one of its ends, that is preferably round in cross section and that has one of its ends formed with a tapered portion which is square or rectangular in cross section so as to be received in the chuck of a drill or like 75 implement which imparts motion to the shank. The opposite, or outer end of the shank 1 is formed with what I will term a head 2. The head has an outer rounded portion, but is provided with equidistantly 80 spaced pairs of ears 3, extending inwardly and arranged in parallelism with respect to the shank. The ears 3 are, however, spaced a suitable distance from the shank.

On the shank 1 there is a slide in the nature of a sleeve 4. The sleeve is provided with equidistantly spaced radially disposed ears 5. The ears 5 are arranged in the same direction as are the ears of the head 2. The ears 5 are of a length equaling that of the 85 sleeve, and the opposed pairs of ears 5 have elongated slots 6 therethrough.

On the shank, between the head 2 and the sleeve 4, is a comparatively light helical spring 7.

Between each pair of ears 3 there is pivotally secured a link 8. Between each pair of ears 5 there is a link 9. Each of the links 9 has a transverse lug or pin 10 that is received in the slots 6 of the respective pairs 100 of ears.

The numeral 11 designates what I will term jaw members. These jaws are in the nature of elongated substantially rectangular blocks, and have their outer surfaces 105 rounded from their sides to their center, as at 12 and their inner surfaces concaved throughout the length thereof as at 13. The concaved portions 13 receive the outer periphery of the spring 7 when the jaws are 110

folded inwardly against said spring. By grooving the inner faces of the jaws, the said jaws may be closely arranged against the spring, so that the same will not perceptibly project beyond the head 2 and the sleeve 4. This permits of the ready insertion of the tool in a comparatively small opening whose wall is to be operated on. The jaws blocks 11 have both of their ends 10 bifurcated, and in these bifurcations are received the oppositely disposed links 8 and 9 which are pivoted to the jaws, as at 14. The upper pivots and those arranged nearest the sleeve 4, provide means for sustaining 15 on the sides of the jaws, flat springs 15. On the outer rounded face and on the sides of each of the jaws there is arranged an abrasive fabric 16. This fabric is preferably in the nature of an emery-cloth, and the 20 portions thereof which are bent over the sides of the jaws are designed to be engaged by the flat springs 15, when the latter are swung against the sides of the jaws.

The operation of the device may be briefly 25 described as follows: The jaws and links are bolted against the shanks, as illustrated in Fig. 1 of the drawings. The tool is then inserted through the bore of a bushing or like article to be lapped. The head 2 may 30 rest on a suitable support. The drill, to which the shank 1 is attached, is then operated. The jaws, are, as stated, in the nature of blocks, and therefore are weighted members. The rapid turning of the shank will 35 cause the jaws to swing outwardly from the shank against the pressure of the spring which is exerted between the head and the sleeve. Thus the abrasive fabrics 16 will be brought against the wall of the opening 40 to be reamed, and the said wall can be properly lapped in an easy, quick and expeditious manner. By the pivotal connection of the jaws with the links, the walls of angle openings as well as the walls of straight 45 openings may be reamed with equal efficiency.

By providing the elongated slots 6 in the outer or upper series of ears the jaws will swing on their links to bring the abrasive surfaces thereof in engagement with the 50 wall of the opening to be lapped even when the device is not arranged directly in a line with the axial center of the said opening. Thus accuracy in this respect is not absolutely essential, as the jaws will effectively 55 act on the work when the tool is held at slight angular positions with respect to the bushing operated on.

The flat springs 15 are comparatively light, but are tightly secured on the blocks 11 so 60 that the same cannot move laterally with respect to the blocks, and consequently, cannot project beyond the abrasive surface to interfere with the operation thereof.

It is thought that the foregoing description, when taken in connection with the drawings, will fully set forth the construction and advantages of the improvement, as well as the operation thereof, without further detailed description. 65

Having thus described the invention, what I claim, is:— 70

A lapping tool comprising a shank having its outer end rounded and forming a head, equidistantly spaced pairs of ears carried by 75 the head and extending inwardly, the same being arranged in parallelism with respect to the shank, radially disposed links pivotally secured to said pairs of ears, a sleeve slidably mounted on the shank, equidistantly 80 spaced radially disposed ears carried by the sleeve having elongated slots therethrough, a light helical spring between the head and sleeve, radially disposed links slidably mounted in the slots of said sleeve, weighted 85 jaw members pivotally connected to the opposed links of the sleeve and head, and an abrasive element clamped to the outer face of the jaw members, substantially as described. 90

In testimony whereof I affix my signature.
CLARENCE SCHERER.
